UNITED STATES PATENT OFFICE.

THOMAS C. HARGRAVE, OF MINNEAPOLIS, MINNESOTA, ASSIGNOR OF ONE-HALF TO JOHN W. COBB, OF SAME PLACE.

MATRIX-MAKING MACHINE.

SPECIFICATION forming part of Letters Patent No. 447,449, dated March 3, 1891.

Application filed May 7, 1890. Serial No. 350,902. (No model.)

To all whom it may concern:

Be it known that I, THOMAS C. HARGRAVE, a citizen of the United States, residing at Minneapolis, in the county of Hennepin and State of Minnesota, have invented certain new and useful Improvements in Matrix-Making Machines; and I do hereby declare the following to be a full, clear, and exact description of the invention, such as will enable others skilled in the art to which it appertains to make and use the same.

This invention relates to machines for making matrices for stereotypes by the consecutive indentation of the various characters constituting the matter to be reproduced into a sheet, strip, or slab of pasteboard, papier-mâché, blotting-paper, wood, or other plastic material.

This invention embodies an improvement on the matrix-making machine shown and described in my application, Serial No. 335,067, filed December 26, 1889.

The object of the same is to materially cheapen the cost of the machine by introducing, wherever possible, straight work for the cylindrical and toothed arrangements involved in the disks, cogs, serrated edges, &c., of the machine disclosed in the above application, and by considerably reducing the number of parts.

The invention relates more specifically to the die-selecting device, including the die or punch carrier and the means for actuating the same to bring the punch of the desired character to the impression-point, to the letter-spacing device or the device for feeding the matrix-carriage along before each impression or indentation sufficiently for the character to be impressed, and the impression or indenting device.

In the present invention I have substituted for the shifting and rotating die-wheel in my former construction a die-carrier movable longitudinally of the machine and provided with die-containing channels, each carrying a row of separate dies, which rows by the key-lever are shifted transversely to the longitudinal movement of the die-carrier. By these two movements I am enabled to carry any desired

die opposite the indenting-point. This construction, by eliminating the die-wheel and cogs for imparting motion thereto, enables me to introduce straight work throughout for these parts, and the dies can be produced more cheaply than when seated on the disk, and have, moreover, the advantage of ready interchangeability. I also reduce the motion of the lever considerably by reducing the character-board in size, and at the same time preserve all the accuracy of the larger character-board by connecting the key-lever for selecting the characters with a pointer or needle extending over the character-board on which the characters are more compactly arranged. The work of the operation is thus made less tiresome, being reduced to a wrist-motion only. Moreover, I substitute for the pawl and serrated strip for advancing the matrix-carriage step by step for letter-spacing a plain strip and a sliding clutch-block so arranged as to grip the strip on its forward movement and to release it on its return, ready for the next spacing operation. I have also materially simplified the construction of the arm which controls the extent of letter-spacing.

Other features of my invention will be pointed out in the specification and covered in the claims.

In order to explain my invention more fully, I will now give a detailed description of a machine embodying what I consider the best form of carrying the said invention into effect.

Figure 1 represents a side elevation partly in longitudinal vertical section; Fig. 2, a plan of the same. Figs. 2^a and 2^b are detail views illustrating the relation of the key-lever to the pointer; Fig. 3, a vertical transverse section on line x x, Fig. 1, looking in the direction of the arrow x; Fig. 4, a rear elevation partly in section; Fig. 5, an end view of the matrix-carriage; Fig. 6, a detail view of the mechanism for adjusting the letter-spacing; Fig. 6^a, a view of the compound spacing-plate developed into a plane; Fig. 7, a detail front elevation of the punch or die carrier; Figs. 8, 9, and 10, detail views of the said die-carrier;

Figs. 11, 11^a, 12, 13, and 14, detail views of the letter-spacing device, and Fig. 15 an isometric view of the die-shifter.

The same characters of reference designate 5 the same parts throughout the drawings.

The machine embodying my invention embraces, broadly, a die-selecting device, a spacing device, and an indenting device. I will consider these in the order named.

10 *The die-selecting device.*—This device includes a number of parts which are identical with what is embodied in my aforesaid application, and which I will briefly point out before setting forth the features forming part 15 of my improvements.

The table or bed A of the machine is provided with a stud A' rising therefrom and encircled by a hub A², held in place by headed screw a, whose head projects beyond the stud 20 and bears down on the upper edge of the said hub, which is preferably undercut or rabbeted to make the top of the screw-head flush with the upper edge of the hub, as shown. An arm a', extending horizontally outward 25 from the hub A², has hinged to it at a² the horizontally-swinging key-lever A³, extending forward under the flaring or inclined character-board A⁴, and above the notched spacing-plate A⁵, preferably in the form of a compound plate, the one plate having uniform notches and the other sliding with respect to the same, and having variable step-shaped notches for the purpose of adjusting the spacing to the character selected, all as set forth 30 in my previous application and shown in Fig. 6^a. The key-lever is provided with the boss a⁶, carrying the spring-stud a⁷, provided with a knob or handle a⁸, the stud a⁷ being adapted to impinge against the contact-strip a⁹ after 35 the key-lever has reached the bottom of the notch opposite the same, for the purpose of closing a circuit for indenting the matrix, all as set forth in the former application. In the said former application the key-lever served 40 upon being swung around horizontally to rotate a die-wheel to bring the desired character on its periphery into printing position, suitable gearing being interposed between the said lever and die-wheel. This die-wheel 45 was also capable of shifting upon its bearings to bring one or the other of a number of annular rows of characters into line with the printing position, the shifting being performed by a mechanism substantially the 50 same as that herein employed for longitudinally shifting the die-carrier C, forming part of my present invention, and which mechanism consists, essentially, of the forked arm B, attached to the lever B' B², pivoted to the 55 table B³ at b⁴, and whose upper arm B² is made elastic and carries a pin b⁵, whose lower end is made to engage with one or the other of a 60 number of perforations b b' b² b³, according as one or the other row of dies is to be brought 65 into line with the indenting-point.

One of the objects of my present invention

has been to substitute a device for the above rotary and shifting die-wheel, in which the number of parts are considerably reduced, while the cogs and round surfaces are entirely avoided and straight work substituted. For this purpose I have devised the following construction: The die-carrier C contains a number of die-containing channels, in the present case open at top and bottom, as shown, 75 and consists of a number of parallel vertical plates C', arranged transversely of the bed of the machine. These plates C', five in number, are removably secured to two end blocks C² C² by suitable tongues or tenons on the 80 plates C', fitting into mortises in the end blocks, the exterior plates being held in place by screws or otherwise, all as shown particularly in Figs. 2 and 7. The plates C' are provided with the horizontal ribs c and the top flanges c² for the purpose of guiding and supporting the dies or punches c³, provided with nicks to correspond to the ribs and flanges. One of the outer plates C' is provided with a dovetail or other guide c⁴, as shown, whose office is to hold and guide the die-shifter D, and which is shown in detail in Fig. 15. The ribs c and flanges c² also serve to guide the tongues d² of the die-shifter, referred to below.

The die-shifter consists of the vertical body 95 d, having the two arms d' d', which extend over the top of the die-carrier C, each arm having a number of tongues d², corresponding to the number of slots in the die-carrier and extending down into the same, as shown in Fig. 3, 100 to embrace the line of type in each channel. From the vertical body d extends the bracket d³, preferably in the shape of a fork, as shown, and from the arm a' on the hub A² extends downwardly the stud d⁴, engaging the forked 105 bracket d³, whereby when the key-lever A³ is swung around the rows of dies in the slats of the die-carrier are moved transversely.

It will be noted that by having the die-channels and also the die-shifter open at top and bottom, as in my preferred construction shown, I gain the important advantage of permitting the plunger which forces the dies into the matrix-blank, and which will be described farther on, to act directly against the 115 ends of the dies, whereby the great pressure necessary to produce a sufficient indentation can be obtained. This result could not be obtained if the die-channels and shifter were not open at both top and bottom. This arrangement also enables me to place the dies with their indenting-faces downward, whereby I am enabled to provide a very simple arrangement of the support for the matrix-blank and to keep the die-faces free from 120 dust.

For the purpose of making the die-carrier capable of longitudinal or to-and-fro movement to bring one or the other row of dies into indenting position, I provide the end blocks C² C² with dovetails engaging similar 130 grooves in standards C³, rising from the bed

of the machine, and I attach the ends of the prongs b^6 of the forked arm B , already described, to these end blocks.

It will be noted that the character-board A^4 in the present instance is considerably reduced in size, extending over only about one-half the width of the table B^3 , the characters being arranged thereon more compactly—for example, by distributing the letters, numerals, and punctuation-marks each over two rows, as shown, or more, if desired. In order to combine sufficient accuracy with this compact arrangement, I have provided an index or pointer B^{10} , connected with the key-lever A^3 and extending entirely across the character-board. The arrangement of this part of my invention is more particularly shown in Figs. 2, 2^a, and 2^b. By turning to these figures it will be seen that the character-board A^4 is provided at its lower rim with a bead a^{10} , which is engaged or embraced by the sleeve b^{10} , forming part of the pointer B^{10} , mounted on the character-board, and which, for the purpose of holding said pointer steady, extends a considerable distance beyond the same at both sides. Secured to the sleeve b^{10} is the fork b^{11} , extending downwardly and straddling the key-lever, whereby motion is imparted to the pointer from the latter and the desired character may be readily selected. The key-lever and pointer are thus loosely connected, so that the key-lever, while adapted to carry the pointer over the key-board, may still be depressed at any point.

Where the character-board is arranged at one side of the machine, as in the present instance, I provide the arm a' , which carries the key-lever, with a spur a^{10} , from which the stud d^4 , already referred to, extends.

The operation of the parts thus far described is similar to that in my aforesaid application—that is to say, by causing the pin b^5 of the arm B^2 to engage one or the other of the perforations b^5 , &c., I place one or the other row of dies c^8 into line for indenting. Then by swinging the key-lever to one or the other point on the character-board A^4 , I cause the stud d^4 , engaging with the bracket d^3 , to carry the die-shifter along to bring the die corresponding to the desired character opposite the indenting-point, to be acted upon by the indenting mechanism to be described farther on.

The arrangement of the character-board with the pointer extending across the same enables me to considerably reduce its size, and thereby reduce the extent of movement of the arm of the operator. The operation of the machine is thus rendered less tiresome.

The letter-spacing device.—As in my former machine, I provide a matrix-carriage E , carrying two rollers $E' E^2$, for carrying and feeding the matrix-blank line by line, the upper roller E being yieldingly forced toward the lower roller by spring-bearings, and the carriage being guided by a dovetail e and a corresponding groove. The line-spacing is here

again performed by means of a ratchet-wheel e' , attached to the end of the journal of the roller E' , (see Fig. 5,) actuated step by step by the pawl-lever e^2 , which is forced back against the stress of spring e^3 by the impingement of its upper arm against the incline e^4 , Fig. 2, at each return of the carriage to the initial position. A shaft F , mounted in standards $f f$, rising from the bed of the machine, is provided at one end with an arm F' , urged upwardly by a spring f' against a flange f^2 on a sliding piece, preferably in the form of a sleeve F^2 , encircling the hub A^2 and normally held upward by spring f^3 . It is in the novel arrangement of the device for moving this carriage forward preparatory to the indentation of each character and in the new mode of adjusting or regulating the extent of feed or letter-spacing that my improvement in this part of the machine, which will now be described, consists, and for this purpose special reference is had to Figs. 6 and 11 to 14. At the rear end the vibratory shaft F is provided with a depending arm F^{21} . The matrix-carriage E is provided at its rear face with the horizontal flanged rib E^3 , preferably having the upwardly and downwardly extending flanges $e^5 e^6$, and which is embraced by a sliding frictional clutch-block F^3 , having grooves to correspond to the flanges $e^5 e^6$, and in the present instance having journaled therein the dog F^4 , whose journal is cut away or cam-shaped, as at f^4 , to preserve the continuity of the groove, as best shown in Figs. 12 and 14. A spring F^5 , whose motion is preferably limited by an abutment f^6 , tends to force the sliding block F^3 in the direction of the arrow 2 and toward the arm F^{21} . The operation of these parts is as follows: When the arm F' is depressed by the depression of key-lever A^3 and intermediate parts, the arm F^{21} is turned in the direction of the arrow, Fig. 11, and by impinging against the dog F^4 the journal thereof is first turned, so as to cause the cam-surface f^4 to bind against the rib E^3 . The further movement of the arm F^{21} then carries the block F^3 , and with it the rib E^3 , to which it is now locked, and the carriage, along sufficiently for the spacing of one letter. Upon releasing the key-lever the arm F^{21} flies back and the spring F^5 slides the block F^3 , which is now released or unlocked, back to its initial point, while the carriage remains in its advanced position. The carriage is thus fed forward one step at each depression of the key-lever, and the extent of its forward feed can be regulated with perfect accuracy and nicety by the extent of depression of the arm F' . This result marks a great improvement over the pawl and serrated edge employed in the machine shown in my aforesaid application, inasmuch as there must always be some lost motion in such a construction however fine the serrations are made. My present spacing device, moreover, possesses the important advantage that the omission of the serrations on the rib

E^3 considerably reduces the cost of manufacture.

While I consider the clutch-block and the strip on which it is mounted best for the purpose, still it is manifest that the same may be modified considerably without departing from my invention, all that is required being that the same is provided with a movable part, which carries the carriage forward by friction when the carriage is urged in one direction and releases the same on the return of the carriage.

Turning now to Fig. 6, it will be seen that the arm F' , which governs the extent of feed of the carriage, is made adjustable, so as to bring the contact-point f^{10} , which bears up against the flange f^2 of the sliding piece F^2 , nearer to or farther from the pivotal point or shaft F . For this purpose the said arm F' passes through a slot in the shaft F , being held in any position of adjustment by a set-screw f^{11} . By this arrangement of the arm F' , which, it will be noted, is far simpler than the construction for the same purpose in my aforesaid patent, I still further reduce the number of parts and cost of manufacture.

The indenting device.—As in my previous application, I provide a single contact-strip G , arranged in proximity to the spacing-plate A^5 and adapted to be struck by the spring-stud a^4 , as the knob a^5 is depressed after the key-lever has reached the bottom of one of the notches in said spacing-plate. The circuit is again completed by the circuit-wires G' , (deriving their electricity from any suitable source, as indicated at g .) the binding-post G^2 , the electro-magnet G^4 , and the binding-post G^3 , whence the current passes to the key-lever by means of the spring G^5 , attached to the top of the key-lever, as shown, which in the present invention serves the double purpose of conducting the current to the lever and of holding it normally raised to break the circuit.

For the purpose of enabling the key-lever to readily turn on the pivot or stud the key-lever is provided with the rounded bearing or button b^9 , and the spring is secured thereto by the beaded pin b^2 , loosely passing through a hole in the end of the spring. This arrangement involves an improvement over my former construction, inasmuch as one spring here takes the place and performs the functions of the two in the said former construction.

An armature H , attached to the arm H' , pivoted in the bracket H^2 and normally held upward by the spring h , operates the plunger H^3 , through the medium of the pitman h' , every time the magnet G^4 is energized through the depression of the key-lever and knob a^5 . The particular die which is at the indenting-point is then depressed and forced against and into the matrix-blank. The means which permit this depression of the selected die with respect to the die-carrier constitute a part of my present invention and are as fol-

lows, special reference being had to Figs. 7, 8, 9, and 10.

Each one of the ribbed plates C' is provided at the point which when the die-carrier is properly shifted will come opposite the indenting-point (in the present case at the middle of the plates) with a vertical slot c^{10} . Within this slot an inwardly-extending pin, forming the continuation of the rib c , is held upwardly by a spring c^{11} , preferably located in a horizontal slot c^{12} , communicating with the slot c^{10} .

It will be readily understood that whenever the die selected is brought forward, so that its nick engages this yielding pin, the die may be depressed into the matrix-blank by the descending plunger H^3 . It is manifest that many modifications may be devised for this yielding pin and slot without departing from my invention, the essential features of which I conceive to be a type-channel provided with a rib for retaining the type, a portion of said rib being held yieldingly—that is to say, made yielding in the direction of pressure in indenting the matrix, and also independent of and disconnected from the plunger which forces the dies into the matrix-blank. It is essential that this die-forcing plunger be thus independent of the yieldingly-held portion of the rib in order that it may act against the ends of the dies and thus exert the pressure necessary to properly indent the matrix-blank.

Below the die-carrier is located the horizontal stripper-plate I , between which and the bed A the matrix-blank is held, said plate I being provided with a perforation or throat i large enough to accommodate any of the dies and directly under the plunger H^3 . It will be noted that the space between the stripper-plate I and the bed A is made flaring at I' opposite the feeding-rolls $E' E^2$ of the matrix-carriage for the purpose of obviating all difficulty of introducing the matrix-blank into said space.

The carriage is provided with the index or finger J , consisting of a strip of metal suitably bent upward, forward, and downward, and adapted to slide over the scale J' to show the operator at any stage of the work how much space is still left in the line.

While I consider the means shown the best for carrying my invention into effect, still it is manifest that the same may be considerably modified without departing from the spirit of my invention, and I therefore do not desire to confine myself to the means so shown; but

What I claim, and desire to secure by Letters Patent, is—

1. In a matrix-making machine, the combination of a die-carrier having a die-containing channel open at top and bottom with a die-shifter, also open at top and bottom, and means for supporting the dies in the die-containing channel, substantially as described.
2. In a matrix-making machine, the combi-

nation of a die-carrier having a die-containing channel open at top and bottom, and dies contained and supported in said channel with their faces in a downward position with a die-shifter, also open at top and bottom, substantially as set forth.

3. In a matrix-making machine, the combination of a die-carrier having a number of die-containing channels and dies sliding in contact with the said channels with a die-shifter having two arms extending across the channels for embracing the lines of dies in said channels and adapted to move the dies back and forth in the channels, all substantially as described.

4. In a matrix-making machine, the combination of a die-carrier having a number of die-containing channels and dies sliding in contact with the said channels with a die-shifter for moving the dies back and forth in the channels, said die-shifter being provided with tongues entering the die-containing channels and adapted to embrace the lines of dies therein, all substantially as described.

5. In a matrix-making machine, the combination of a sliding die-carrier having a number of die-channels containing a number of dies with a die-shifter for moving the dies back and forth in the channels transversely to the movement of the die-carrier, all substantially as described.

6. In a matrix-making machine, a die-carrier having die-channels and a die-shifter for moving the dies back and forth in the channels and provided with a bracket, as d^3 , in combination with a key-lever and a stud extending therefrom to engage the bracket, all substantially as described.

7. In a matrix-making machine, a die-carrier having die-channels and a die-shifter having a forwardly-extending forked bracket, in combination with a swinging key-lever having a depending stud for engaging with the forked bracket, all substantially as described.

8. In a matrix-making machine, the combination of a die-carrier having die-channels, each channel containing a row of dies, with a die-shifter having a vertical body and arms extending over the die-carrier to embrace the rows of dies and provided with tongues depending into the die-channels, all substantially as described.

9. In a matrix-making machine, the combination of a sliding die-carrier provided with channels containing rows of dies and a die-shifter movable transversely to the sliding movement of the die-carrier and provided with a forked bracket extending therefrom with a key-lever having a depending stud for engaging the forked bracket, all substantially as described.

10. In a matrix-making machine, a die-carrier containing die-holding channels provided with die-retaining ribs and having vertical slots and horizontal slots extending therefrom, in combination with pins in said

vertical slots and extending into the channels into line with the die-retaining ribs and springs located in the horizontal slots and attached to the pins, all substantially as described.

11. In a matrix-making machine, the combination of a die-depressing plunger with a die-carrier provided with a die-containing channel having a die-retaining rib, a portion of which is held yieldingly, and a die-shifter, all substantially as described.

12. In a spacing device for matrix-making machines, the combination of a sliding flanged piece, as F^2 , provided with a flange, as f^2 , with an arm for controlling the carriage-feed, and a vibrating shaft, the arm being held adjustably by the vibrating shaft, all substantially as described.

13. In a spacing device for matrix-making machines, the combination of a sliding flanged piece, as F^2 , provided with a flange, as f^2 , and a slotted vibrating shaft, an arm for controlling the carriage-feed passing through the slot in the vibrating shaft, and a set-screw for holding the arm in position of adjustment, all substantially as set forth.

14. In a matrix-making machine, a matrix-carriage, in combination with a sliding frictional clutch-block and means for causing the clutch-block to grip the carriage on its forward movement and to release the same on its return, all substantially as described.

15. In a matrix-making machine, a step-by-step spacing device consisting of a carriage having a rib carrying a sliding block and a dog having a cam-face journaled therein, in combination with a vibrating dog and means for returning the sliding block to its initial position, all substantially as described.

16. In a matrix-making machine, a step-by-step spacing device consisting of a carriage provided with a rib carrying a sliding block and a dog journaled in the block, the journal being partly cut away, in combination with a vibrating dog and a spring for returning the sliding block to its initial position, all substantially as described.

17. In a matrix-making machine, the combination of a character-board and a pointer mounted on and adapted to slide over the same with a key-lever and means for loosely connecting the key-lever with the pointer, all substantially as described.

18. In a matrix-making machine, the combination of a character-board provided at its lower edge with a bead and a pointer having a sleeve for embracing the said bead with a key-lever and means for connecting the key-lever with the pointer, all substantially as described.

19. In a matrix-making machine, a character-board provided at its lower edge with a bead and a pointer having a sleeve for embracing the said bead and a downwardly-extending fork, in combination with a key-lever straddled by the fork, all substantially as described.

- 6
20. In a matrix-making machine, the combination of a matrix-carriage with a bed and a stripper-plate, the space between the bed and stripper-plate being flared opposite the matrix-carriage, all substantially as described.
21. In a matrix-making machine, an electric circuit for operating a die-plunger, comprising a key-lever included in said circuit and adapted to close the same when depressed and a spring for raising the key-lever and connecting the same with a binding-post in the circuit, substantially as described.
22. In a matrix-making machine, a hori-

zontally-swinging key-lever adapted to be depressed, in combination with a spring attached to the top thereof by a headed pin passing loosely through the perforation in the same and a binding-post in an electric circuit, the spring being connected to the binding-post, all substantially as described.

20
In testimony whereof I affix my signature in presence of two witnesses.
